[57] CLAIM

The ornamental design for a push toy, as shown and described.

DESCRIPTION

FIG. 1 is a front elevational view of a push toy showing my new design, the rear elevational view being substantially a mirror image;

FIG. 2 is a side elevational view thereof, the side opposite being substantially a mirror image;

FIG. 3 is a top view thereof; and,

FIG. 4 is a bottom view thereof.

FIG. 1

FIG. 2

FIG. 3

FIG. 4
